(57) **CLAIM**

The ornamental design for a protector for a wrist watch, as
shown.

DESCRIPTION

FIG. 1 is a front elevational view of a protector for a wrist
watch, showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front, bottom and right side perspective view
thereof; and,

FIG. 8 is a reference view thereof showing the state of use.
The broken line showing of a watch is for illustrative
purposes only and forms no part of the claimed design.
